DEFECT CARD HOLDER

Arthur B. McNabb, Sacramento, Calif.

Application November 5, 1938, Serial No. 238,955

2 Claims. (Cl. 40—17)

This invention relates to defect card holders usually attached to railway cars. Railway cars are often used by railroads other than the railroads which own them, but the owner is responsible for keeping its cars in operating condition. When a car is in need of repairs, the railroad which is in possession of the car places a card in a box provided for that purpose. When the car is returned to its owner, repairs indicated by the cards are made by said owner.

The object of this invention is to provide a sturdy, watertight box having a removable cover and means for attachment to a railway car so that it may serve as a defect card holder.

15 In the drawing:

Fig. 1 is a fragmentary side elevation of a railway car showing a typical application of my invention.

Fig. 2 is a side elevation of my invention.

20 Fig. 3 is a section on line 3—3 of Fig. 2.

Fig. 4 is a section on line 4—4 of Fig. 2.

Fig. 5 is a section on line 5—5 of Fig. 4.

Fig. 6 is a section on line 6—6 of Fig. 2.

The parts of the railway car shown in Fig. 1 are side sill 2; side sheathing 3; side flange 4 of the end wall; lower corner cap 5; bolster connection 6 and defect card holder 7. The defect card holder 7 is shown attached to the bolster connection 6, although it is often preferable to attach it 25 to the side sill, sheathing, door or other easily accessible part of the car.

The defect card holder 7 is a box-like structure having sides 10 and 11; a top 12; a bottom 13; a rigid end 14 and a slidable end 15 which serves 30 as a door to be opened for insertion of defect cards. The sides 10 and 11 are provided adjacent the slidable end 15 with outwardly projecting flanges 16 and inwardly projecting reflanges 17 which form a pair of channels 18. The channels 18 serve as guides for the vertical sliding movement of the end 15.

The top 12 has an upwardly projecting part 25 near the slidable end 15. The upper portion 26 of the end 15 is formed with a depending flange 27 which forms with the upper portion 26 a downwardly facing channel 28 which is arranged to overlie the part 25 and form a watertight seal when the end 15 is in its lowermost or closed position. The channel 28 is provided with closed ends 32, as shown in Fig. 6. A handle 29 for operating the end 15 is preferably formed integral with said end. A clip 30 is provided on the

end 15 to limit the downward sliding of the end 15 and the depending flange 31 on the bottom 13 is intended to engage flatwise with the lower portion of the end 15 to form a seal.

5 The holder 7 is attached to the car preferably by the member 35 secured to one of the sides 11. The member 35 extends beyond the top 12 and bottom 13 and is provided with holes 36 for rivets or bolts used in attaching the holder 7 to the car.

10 The accompanying drawing illustrates the preferred form of the invention, though it is to be understood that the invention is not limited to the exact details of construction shown and described, as it is obvious that various modifications thereof, within the scope of the claims, will occur 15 to persons skilled in the art.

I claim:

1. A watertight box adapted to be attached to a railway car, said box comprising vertical disposed sides and ends and horizontal top and bottom, 20 said sides having outwardly projecting flanges adjacent one of said ends and inwardly projecting reflanges on said flanges to form a pair of facing channels, one of said ends being slidable in said channels, an upwardly projecting part on said top adjacent said slidable end, the upper portion of said slidable end being formed with a depending flange which cooperates with said upper portion to provide a downwardly facing channel arranged to overlie said part and form a watertight 30 seal, means to close the ends of said last mentioned channel, and means to secure said box to a railway car.

2. A watertight box adapted to be attached to a railway car, said box comprising vertical disposed sides and ends and horizontal top and bottom, 35 said sides having outwardly projecting flanges adjacent one of said ends and inwardly projecting reflanges on said flanges to form a pair of facing channels, one of said ends being slidable in said channels, an upwardly projecting part on said top adjacent said slidable end, the upper portion of said slidable end being formed with a depending flange which cooperates with said upper portion to provide a downwardly facing channel 40 arranged to overlie said part and form a watertight seal, means to close the ends of said last mentioned channel, and vertically disposed members in spaced relation to one of said sides and extending beyond said top and said bottom 45 for attachment to a railway car.

ARTHUR B. McNABB.
